UNITED STATES PATENT OFFICE

MARTIN J. LIDE, OF BIRMINGHAM, ALABAMA

JIGGING MECHANISM

Application filed August 2, 1924, Serial No. 729,672. Renewed August 6, 1928.

My invention relates to certain new and useful improvements in jiggling mechanism, which in the embodiment presented is more particularly designed for the treatment of 5 coal but which is obviously applicable to the treatment of other materials which require separation by flotation methods.

In Letters Patent No. 1,491,870, issued to me on the 29th day of April, 1924, I have 10 illustrated and described a jiggling mechanism wherein opposing synchronous impulses of water were admitted to the jig tank below the screen under the control of valves substantially co-extensive in length or width 15 with the side or end of the screen, according to their arrangement. One of the principal objects of my present invention is to improve and perfect the valve mechanism for controlling and regulating the impulses of 20 water delivered to the jig tank and to this end I contemplate, broadly speaking, the utilization of a multi-ported valve whereby, with a relatively short movement, the ported area of the valve can be fully opened and 25 closed, such movement being either reciprocatory, oscillatory or rotary, as may be desired.

More particularly my invention contemplates certain improvements in the preferred type of multi-ported valve which is of the 30 oscillatory type and designed so that with a minimum friction and a relatively short stroke the valve may be fully opened or closed and permitting the opposing valves to be very simply connected for both a joint and 35 synchronous movement. Moreover, the valve lends itself to simplicity in construction, accessibility, minimum friction, and a low cost both for production and maintenance.

My invention also contemplates the designing 40 of the jig tank below the screen with passages for the water impulses which are formed by curved surfaces designed for eliminating any settlement or eddy space and causing the impulses to flow with the least possible friction or disturbance directly from the valves to the jig screen.

My invention relates to certain improvements 45 in adapting the type of jig in question for multi-stage jiggling wherein refuse of relatively decreasing specific gravity is suc-

sively removed by varying the intensity and frequency of the impulses or of the agitation imparted to the material on the jig screens. According to my present invention, the different treatments in the successive jigs is controlled by several factors, such as the difference in head between the supply water and the jig tank, and the variation in the intensity, duration and frequency of the impulses, which factors are severally subject to control whereby I effect the desired treatment at each stage. In view of the fact that there is, in the type of jig in question, a uni-directional flow of water through the jig screen, which causes a relatively large flow of water, it is desirable 60 to make provision for utilizing this in the successive stages and to this end my invention contemplates the setting of the successive jigs at decreasing levels throughout the stages and utilizing the water as it flows from one 65 to another tank to supply the needed head at each tank to induce pulsations of the required velocity in each stage without any other power than gravity. In order to make the water thus successively available for the jigs 70 I provide a screen between each two stages in the sluice way over which concentrates from one jig tank flow to the next succeeding jig, the water removed by the screen from the concentrates being delivered to the supply tank 75 of the succeeding jig and such part thereof as is in excess of the requirements of the secondary jig, is diverted by a pass means to the settling tank or the return circuit.

My invention further contemplates improvements in the means for controlling the slate gate so that the extent to which the gate is opened and its timed relation to the impulses of water flowing through its respective jig screen can be controlled and varied 85 so as to produce the best operating results. My invention contemplates that the extent of the slate gate's opening shall be controlled by a change in leverage in its actuating mechanism, and that its timed relation to the impulse shall be controlled by an adjustment of its actuating mechanism in combination with an overlapping of the gate below its port.

My invention further contemplates an improved type of jig screen designed to elimi-

nate dead spaces on which material can rest above it and to reduce to a minimum the loss of head to impulses flowing through it.

My invention also comprises the other 5 novel details of construction and arrangement of parts, which in their preferred embodiments only are illustrated in the accompanying drawings which form a part of this specification, and in which:—

10 Fig. 1 is a plan view of a single stage multiple jig in accordance with my invention.

Fig. 2 is a cross-sectional view on the line 2—2 of Fig. 1.

15 Fig. 3 is a view corresponding to Fig. 2, showing a modified type of valve and slate gate operating mechanism.

Fig. 4 is a vertical cross-sectional view taken on the line 4—4 of Fig. 1.

20 Fig. 5 is a detail view in perspective of the preferred type of valve with its seat partly broken away.

Fig. 6 is a transverse cross-sectional view through a portion of the valve in its seat.

25 Fig. 7 is a detail view illustrating the slate gate operating mechanism.

Fig. 8 is a vertical cross-sectional view through the slate gate and the discharge end of the jig screen.

30 Fig. 9 is a perspective view of the discharge end of the jig screen with the slate gate, weir plate and sluice way, partly shown.

Fig. 10 is a detail cross-sectional view through a part of the jig screen.

35 Fig. 11 is a plan of a multi-stage jig in accordance with my invention.

Fig. 12 is a longitudinal vertical cross-sectional view taken on the line 12—12 of Fig. 11.

40 Fig. 13 is a detail view of a part of the screen between the jigs.

Similar reference numerals refer to similar parts throughout the drawings.

In the embodiment of my invention illustrated in Figs. 1 to 10, excepting Fig. 3, I 45 show a jiggling mechanism comprising a storage bin 1 suitably supported by columns 2 and having a rotary feeder 3 which controls the rate of feed of the material to be jiggled down the chute 4 and onto the screen 5 in 50 the jig tank 6. The screen, as shown more clearly in Fig. 10, is formed by a series of bars having their ends shaped to abut and rest on the seat 7 provided in the end walls 8 and 9 of the jig tank. The intermediate or 55 working portion 10 of the bars is shaped to form between them passages for the flow of the water which converge upwardly to a minimum intermediate orifice and then diverge to the top surface of the screen, thus providing 60 passages of an approximate Venturi type whereby the water passes through the screen with the minimum loss of head. There are no dead spaces left on top of the screen since the screen bars along their upper surfaces 65 are reduced to sharp edges. This leaves

no surface upon which any particles on the screen can rest without being subject to impulses of water flowing upwardly through the screen.

At its discharge end the wall 8 is offset to provide a guide 11 into which the slate gate 12 can drop for a substantial distance below the top level of the screen. This overlapping of the gate is provided as a means to permit the extent of its opening movement to be controlled in the manner which will be later described. The gate itself works in guides 13 set in the concrete or other structure of the jig and this guide also carries a weir plate 14 which is adjustably bolted to it. An angle 15, secured in the masonry, supports the upper end of a sluice way 16 down which the concentrate and overflow water pass to the settling tank 17, where a baffle 18 is provided about the point of inflow of the water so as to prevent undue disturbance or waves in the settling tank. The slate or refuse is delivered by a chute 19 into a compartment 20 in which a drag conveyor 21 works and acts to convey the slate or refuse to any suitable discharge.

The side walls 22 of the jig tank terminate below the screen and with the U-shaped converging bottom walls of the jig tank form curved passages co-extensive in length with the length of the screen and meeting along a medial line between side walls 22. These curved passages 23 afford unrestricted communication between the lower jig tank and the supply compartments 24 on each side. To these compartments 24 water is supplied from a return circulation or from any source of supply and is normally maintained at a mean level substantially higher than that in the jig tank, the difference in elevation being in accordance with the intensity desired for the impulses. At the bottom of each supply compartment I interpose a valve seat 25 which is suitably supported by angles 26 anchored in the concrete and this seat is semi-circular in transverse vertical cross section and has side flanges 27 which overlap the angle irons 26. Semi-circular walls 28 close the seat at each end and are disposed to abut the end walls of the compartments. The seat is provided with a series of ports 29 which are preferably elongated in the direction of the length of the seat and arranged in transverse rows so as to form a multi-ported seat for the semi-circular oscillatory valve 30, which itself is provided with transverse series of ports 31 lying in the same transverse planes with the series of seat ports 29 and corresponding in size and shape therewith. The valve is provided with spiders 32 which are clamped on a shaft 33 that is journaled in bearings 34 on brackets provided on the end walls 38 of the valve seat. An operating arm 35 is connected to the clamp member 36 which is bolted about the shaft 33 to flanges on the spider 32, thereby clamping the valve 30 to its supporting shaft.

33. The port arrangements of the valve and seat are such that a relatively small angular movement of the arm 35 will oscillate the valve from full open to full closed position and vice versa. The valve mechanism described is utilized in each supply compartment for each jig tank and where a battery of jigs are provided side by side the operating arms 35 of all of the valves are preferably arranged in alignment so that they can all be hingedly connected overhead to a common reciprocating actuator 37. As shown, this actuator is an I-beam that is supported by the arms 35 and at one end is hingedly connected to a pitman rod 38 which is driven from a crank disk 39 on a shaft 40. The shaft 40 is mounted in suitable bearings 41 and is driven by a chain 42 from a back geared motor 43. By this means the actuator 37 is reciprocated and the several valves 30 are moved in unison to open and close the seat ports and cause impulses of water to flow through the curved inlet passages 23 to the tank below the jig screen. These impulses will flow up through the spaces between the screen bars in the manner above described and will act efficiently to effect the separation of the lighter from the heavier matter. The lighter will pass over the slate gate 12 and weir plate 14 and will be discharged along with the overflow water from the jig through the sluice way 16.

The slate gate control mechanism in the preferred embodiment illustrated, comprises a cam plate 44 carried by the actuator 37 and having its double reverse curved surface engaged by a roller 45, journaled in a rocker 46 that is pivotally mounted at an intermediate point in the bracket 47 and has its other end connected by a rod 48 to one end of an overhead rocker arm 49. This rocker arm 49 is pivoted at its center to a bracket 50 carried by an overhead support 51 and its other end is connected by a rod 52, with a turn buckle 53 provided therein for adjustment purposes, to a clamp 54 which is adjustable along a lever 55 which is fulcrumed to the upper end of the bracket 47 and at its free end carries a curved face 56 struck on an arc from its fulcrum. A chain or flexible connection 57 is attached at the upper end of the curved face 56 and at its lower end is suitably connected by divergent chains 58, or the like, to each end of the slate gate 12. The clamp 54, as more clearly seen in Fig. 7, is provided with a set screw 59 by means of which it may be clamped on the lever 55 at the desired distance from its fulcrum. The cam 44 is so disposed upon the actuator that during each cycle of a valve 30, which cycle involves fully opening it and then closing it for a period of rest, the slate gate will be raised and lowered, the relative timing of its movement being dependent on the extent to which it is permitted to overlap the end wall 8 by dropping into the groove 11 and this overlap is controlled by the adjustment allowed by the turn buckle 53. For controlling the extent to which the slate gate is raised, the clamp 54 can be adjusted back and forth along the arm 55 and the length of the leverage determines the extent of the opening.

A sluice way 60 surrounds the inlet tank 17 and takes the overflow therefrom, delivering it down the inclined sluice way walls 61 to an inlet pipe 62 of a pump 63, which, under control of valve 64, delivers the water by means of a pipe 65 to a manifold chamber 66. From this manifold chamber the water flows under control of valves 67 to the water supply chamber 68 of each jig, these chambers for each respective jig being kept separate by a partition 69 so that either jig may be cut out of service when desired.

With my circulation system therefore the water overflowing from the settling tank 17 returns by the sluice way 60 and pipe 62 to the pump 63 and thence is delivered to the manifold chamber 66 and under valve control delivered to the supply chambers 68 of the several tanks, whence it flows to the supply compartments 24 and hence under control of the valves 30 is delivered through curved passages 23 into the jig tank below the screen and forced upwardly through the latter and flows to the settling tank with the overflow from the jig.

The embodiment of my invention in a multi-stage jiggling mechanism is illustrated in Figs. 11 to 13. Here the construction of the jiggling tank proper, together with its bin and feed mechanism is the same as described in connection with the single stage jig. The only difference is that here the jigs are not arranged in battery form and hence the pipe 65 from the pump leads directly into the supply chamber 68 of the initial jig whence it passes to the supply compartments 24 flanking such jig on each side and there is controlled by the oscillatory valve mechanism already described, to form pulsations which enter the jig tank. Also the slate gate mechanism, weir plate and sluice way are all the same, except that the sluice way 16^a stops with the far wall 69 of the slate compartment 20, and this wall 69 forms one wall of the supply chamber 68 for the next lower jig tank 6. This latter chamber 68 communicates with the supply compartments 24 on each side of such secondary jig and from these the water under control of the oscillatory valve mechanism described, enters the secondary jig tank, flows up through the screen 5 therein, and overflows into a sluice way 16, corresponding to that shown in Fig. 4, and thence passes to the settling tank 17 or to a succeeding stage or to the return circuit, as may be desired. The supply pipe 62^a for the pump leads from the sluice way 60 into which water overflows from the settling

tank. The sluice way 16^a between stages delivers the water and concentrates passing from the initial jig tank over a screen 70 which extends across the supply chamber 68 for the secondary jig. The screen is formed by bars mounted on cross rods 84 with spacer washers 85 separating them, as will be seen more clearly in Fig. 13. This causes the water overflowing from the initial jig to pass directly into the supply chamber 68 of the next jig and thence to flow to the supply compartments 24 for such secondary jig which is at a lower level than the initial jig.

Inasmuch as it will ordinarily be desirable to subject the material in the initial jig to more violent agitation to separate the heaviest or coarsest matter therefrom, such, for instance, as the slate in coal, leaving the bone coal to be separated from the coal in the secondary jig, it follows that there will be a greater volume of water needed to give the high velocity pulsations in the first jig than is required to give the lower velocity pulsations in the second jig where the materials to be treated, being of much closer relative specific gravity, will require much less violent agitation for their separation. To prevent this excess of water from the first jig interfering with the operation of the secondary jig, I provide by-pass sluice gates 71 at the lower end of the latter jig's supply compartments 24 and by raising or lowering these sluice gates more or less of the water can be by-passed over extensions 72 of the sluice way into the settling tank 17. By this arrangement water impulses of long duration and relatively large volume can be delivered to the initial jig and impulses of much shorter duration and lesser volume can be delivered to the secondary jig, so that the mechanism will efficiently remove the heavier matter in the primary treatment jig and the lighter material in the secondary treatment jig. The bone coal, for instance, recovered from the slate compartment of the secondary tank is available for fuel purposes and leaves the concentrate delivered to the settling tank after the two treatments practically free of all matter which it is desired to remove therefrom. The operation of each of the tanks in the multi-stage series is identical with that described for an individual tank.

In the operation of my invention as applied to the single stage jig, the difference in head between the supply compartments 24 and the jiggling tank 6 is first established, the difference being such as to produce impulses of the desired velocity. The next adjustment is that of determining the desired frequency for the impulses, and this is controlled by the speed of the motor drive to the reciprocating actuator, it being contemplated that the R. P. M. of the crank can be varied in any well known manner.

The next control feature to be determined is the duration of the impulses which is relative

to the periods of rest or subsidence for the material being acted upon in the jig tank, and this duration factor is controlled by the ratio of the width of the valve ports and that of the blank spaces between seat ports, the greater the relative width of the blank spaces the longer the period of subsidence. It is contemplated that seats for the valves having blank spaces of various widths will be provided. Having adjusted these control factors according to the work desired in the jig, the mechanism is started up, the material to be treated is fed to the jig, the slate or refuse bed accumulates on the screen and the reciprocations of the actuator impart vertical movements to the slate gate which must be timed relative to the impulses and raised to a height which will give the best results for the discharge of the refuse or slate. The timing of the movements of the slate gate relative to the impulses is effected by the position of the slate gate cam 44 on the actuator, this being set to the desired position. The extent of the gate's effective opening movement is then adjusted by setting the clamp 59 at the desired distance from the fulcrum of the lever 55, and finally the extent to which the gate rises above the screen bed in the jig is determined by an adjustment of its turn buckle 53 which regulates the extent of its overlap below the screen bed. Having adjusted the slate gate movements in the several ways above described, the mechanism is ready for continuous operation and the concentrates pass over with the overflow water to the settling apparatus and are there treated in the customary manner.

In the operation of the multi-stage jig the two successive jigs operate in the same manner but generally the secondary operates under a less difference in head between the jig tank and its supply compartments 24, thus causing impulses of lesser intensity in the secondary jig. All overflow water from the primary jig passes through the screen 70 in its sluice way 16^a and flows to the supply compartments 68 for the secondary jig, and since the latter will have impulses of lesser intensity there would be a surplus of water for the secondary jig were it not diverted by the by-pass sluice gates 71 to the settling tank or return circulation. The important feature of this arrangement is that no additional supply of water is required for any stage after the primary stage since each successive stage can be set at a lower level and the water caused to flow continuously from the primary jig tank through the supply compartments to each jig tank in the subsequent stages.

In Fig. 3 I show a modified type of oscillatory multi-ported valve to deliver the impulses of water to the jig. Here, the supply compartments 24 connect directly with the curved passages 23 which have interposed across them a multi-ported seat 25^a having ports therein like seat 25. These seats 25^a

are arcuate with their concave surfaces facing each other and struck on centers from the axis of a shaft 73 disposed along the apex of the curved walls forming the bottom of the converging passages 23. This shaft 73 projects through an end wall of the jig tank and is operated by an external rocker arm 74 driven by a connecting rod 75 from the eccentric 76. The shaft 73 carries arcuate 10 multi-ported oscillatory valves 30^a, similar to the valves 30, and arranged as they move angularly in the same direction to simultaneously open or close the ports in their respective seats 25^a. The shaft 73 carries an external 15 arm 77 which at its free end is secured to a rod 78 having a turn buckle 79 therein. This rod operates a rocker 80 which by a rod 81 is connected to the cuff 54 on the slate 20 gate lever 55^a, which is here shown curved in order that adjustments of the cuff thereon will not require compensating adjustment of the turn buckle 79. The lever 55^a has a fulcrum 82 on a side wall of the jig tank. This 25 valve and slate gate mechanism will operate like that described above.

I provide any desired number of clean out pipes 83 for each passage 23.

Having thus described my invention, what I claim as new and desire to secure by Letters 30 Patent, is:—

1. A jiggling mechanism comprising a jig tank, water storage compartments along opposite sides of the tank, valve means interposed at the bottom portion of said compartments, a screen bed in the jig tank, and U-shaped passages arranged to deliver pulsations of water from each compartment, which passages converge upwardly towards and meet along a transverse medial line below 35 the screen between said compartments.

2. A jiggling mechanism comprising a jig tank and screen, a supply tank alongside the jig tank and opening thereinto below the screen, and a multi-ported oscillatory valve 45 controlling the delivery of impulses of water from the supply tank to the jig tank below the screen, said valve being substantially parallel and co-extensive with the adjacent side of the screen.

3. A jiggling mechanism comprising a jig tank and screen, a water supply tank alongside the jig tank having communication with the latter below the screen, an accurate multi-ported valve seat interposed between the lower 55 part of the supply compartment and the jig tank, a multi-ported valve mounted to control said seat ports and admit pulsation of water to the jig tank, and means to periodically open said valve.

4. A jiggling mechanism of the multi-stage type comprising at each stage a jig tank having a water supply tank in which the normal water level is maintained substantially above its respective jig tank and in which the water 65 level of each jig tank is maintained above the

level of the supply tank of the succeeding jig, valve means to control the delivery of water impulses from each supply tank into its respective jig tank, a jig screen and slate gate mechanism for each jig tank, sluice ways for conducting the overflow water and concentrates between the stages, a settling tank, and means to return the water therefrom to the initial stage.

5. A jiggling mechanism according to claim 4, in which means is provided to by-pass excess water around secondary jig tanks requiring impulses of lesser velocity than in a preceding jig.

6. A jiggling mechanism according to claim 4, in which means are provided to direct the overflow water from each jig into the supply tank for the succeeding jig.

7. A jiggling mechanism according to claim 4, in which a screen is provided in the sluice way leading to a secondary jig tank and is disposed to deliver the water passing through it to the supply tank of the next succeeding jig.

8. A jiggling mechanism comprising a jig tank having a screen therein and a suitable slate gate, water supply passages leading downwardly along opposite sides of the jig tank and then inwardly under the jig screen and converging upwardly to meet at a point 90 adjacent to the jig screen substantially midway between the supply ends of the passages, said passages being of substantially uniform cross-sectional area throughout, and synchronously operated valve means to deliver 95 pulsations of water under the desired head from said passages to the jig tank below the screen.

9. In a jiggling mechanism, a jig tank having a water supply compartment opening at 100 its lower end, a multi-ported valve in said compartment, means to oscillate said valve, a reciprocatory slate gate for the jig tank, and means to operate the gate by the valve actuating mechanism.

10. In a jiggling mechanism, a jig tank having opposed water supply compartments opening at their lower ends into the tank on opposite sides, multi-ported valves in said compartments, means to oscillate said valves in synchronism, a reciprocatory slate gate for the jig tank, and means to operate the gate by the valve actuating mechanism.

11. A jiggling mechanism comprising a jig tank having a screen and a water supply compartment, an oscillatory valve for controlling the delivery of water impulses from said compartment into the jig tank, a reciprocatory slate gate, a reciprocating actuator connected to said valve to operate it, an element adjustable on said actuator, and means to transmit motion from said element to reciprocate the slate gate.

12. A jiggling mechanism according to claim 11, in which said gate operating con-

nections are adjustable as to length, and the slate gate has a seat extending below the jig screen, which seat said slate gate is adapted to overlap to an extent controlled by said adjustment in its operating connection.

8. 13. A jiggling mechanism according to claim 11, in which the operating connections for the gate comprise a lever connected at its free end to the gate and having the connections which rock it about its fulcrum adjustable from and towards the fulcrum to vary the travel of the slate gate.

10. 14. A jiggling mechanism according to claim 11, in which the actuator is a cam and the gate operating connections comprise a rocker having a roller engaging said cam, said cam being adjustable on the actuator to time the operation of the slate gate relative to the opening of the valve.

15. 15. In a jiggling mechanism, a jig screen, means comprising an intermittently opening valve to admit impulses of water to pass upwardly through said screen, a slate gate raising it in synchronism with the opening of said valve, means to reciprocate the slate gate, means to adjust the height to which the slate gate is lifted above the screen, and a weir plate associated with the slate gate.

20. 16. A jiggling mechanism in accordance with claim 17, in which the weir gate is fixedly mounted on the jig alongside the reciprocating slate gate and adapted to be adjusted to different heights above said slate gate.

25. 17. A jiggling mechanism comprising a jig tank and screen, a water supply tank alongside the jig tank having communication with the latter below the screen, a multiported valve seat interposed directly between the supply and jig tank and having blank spaces between its ports, a multiported valve mounted to control the seat ports, the width of the blank spaces between the ports of the valve seat bearing a ratio to the width of the valve ports commensurate with the period of subsidence desired in each valve cycle, and means to operate the valve to periodically open and close said seat ports.

30. In testimony whereof I affix my signature.
50. MARTIN J. LIDE.
